UNITED STATES PATENT OFFICE

JOSEPH A. HOEGGER, OF JERSEY CITY, NEW JERSEY

WALL BOTTLE OPENER

Application filed January 14, 1928. Serial No. 246,669.

My invention relates to improvements in bottle openers such as are adapted for attachment to a wall and for use in removing bottle caps. The object of my invention is to produce a strong, rigid, simple device of this kind, which can be easily attached to a wall or support, and will project out so as to conveniently engage the cap of a bottle and permit its quick removal. A further object of my invention is to produce a structure of this kind which can be swaged or made with a die, and will have such shape and clearance that it can be rapidly and economically produced. A further object of my invention is to produce a structure of this kind having a stiff, rigid member projecting from the wall in the form of a post, and with the cap removing parts formed directly in the outer end of the post, and preferably with all the parts lying within the plane of the post sides, to the end that the structure can be economically produced and efficiently used.

Such devices are usually in exposed positions, and my invention is intended further to produce a structure which because of its shape will lend itself to a handsome finish, and will be of an ornamental nature.

Reference is to be had to the accompanying drawings forming a part of this specification, in which similar reference characters indicate corresponding parts in all the views.

Figure 1 is a front elevation of the bottle opener embodying my invention.

Figure 2 is a side elevation of the bottle opener.

Figure 3 is a view of the base with the supporting screws in section.

Figure 4 is a longitudinal vertical section.

Figure 5 is a detail of a type of supporting member.

Figure 6 is a face view of the bottle opener showing another way of fastening it to a wall or support, and

Figure 7 is a vertical longitudinal section of the structure as shown in Figure 6.

The bottle opener is preferably provided with a base 10 flat on the back side so that it can fit snugly against a wall or support,

and this base merges into a rigid substantial post which projects outwardly from the base and is slightly tapered on the upper and lower sides 11 which are oval in cross section as the drawing shows. The side parts 55 of the post are preferably flat as shown at 12 in Figure 1. The tapering of the post is somewhat exaggerated in the drawing, and the object of this is to make the structure so that it can be swaged or formed 60 with a die, which makes a better, stronger, and handsomer article than if a casting is used. Moreover, a structure made in this way lends itself to a much handsomer finish.

The post at its outer end is formed on the 65 under side with an upturned or projecting claw 13 adapted to engage under the cap of a bottle, and with an overhanging member 14 at the upper side spaced from the claw 13, while the recess 15 is made transversely 70 through the end of the post as shown clearly in Figure 2. This recess is formed for clearance, and the back wall of the recess from its middle portion to the upper part 75 of the member 14 is inclined. Thus a bottle with a cap can be manipulated so that the cap will enter the recess 15, the claw 13 will engage under the cap, and the opposite part of the cap will have a bearing on the inclined under surface of the member 14; then 80 by lifting slightly on the bottle the cap will be easily pried loose.

By reference to Figure 1 it will be seen that the sides and top and bottom of the parts 13 and 14 lie within the plane of the 85 post, thus making it easy to produce the tool, and also leave smooth side parts which are not apt to engage extraneous objects.

The base 10 can be fastened to a wall or support in any convenient way. I prefer to 90 use a hidden fastening so that the structure will be handsomer and will at the same time be very rigid. Such a fastening is shown in Figures 3, 4 and 5. The back of the base 10 is recessed as shown at 16 to receive a plate 17 which is firmly secured in place by screws 18 or the like, and has a tongue 19 fitting in a complementary recess of the base. If it is placed in vertical alignment with the screws 18 and with the centre 95 100

of the post above referred to, the post will be sure to project at the right angle. The plate 17 has a stem 20 projecting outward and entering a recess or bore 21 in the 5 post. The stem is recessed as shown at 22 to receive a fastening screw 23 entering through a hole 24 and impinging on the inclined wall of the recess 22 so that when the screw is tightened up it will follow the incline and serve to draw the base 10 snugly to position. The particular means of fastening above referred to is explained so that there can be no misunderstanding, but this fastening feature is also shown in my Letters Patent of the United States No. 15 1,636,364, dated July 19th, 1927.

Instead of using the above described and preferred fastening, the base may be provided with holes 25 (see Figures 6 and 7) 20 to receive fastening screws 26, or the device can be fastened in other ways without affecting the invention.

I claim:—

A wall bottle opener having a relatively 25 broad flat back base adapted for attachment to a wall, said base merging in an outwardly extending post which is integral with the base and which is of progressively decreasing cross sectional size from the base to the 30 outer end of the post, said post being transversely slotted across the outer end and terminating on the upper side in a projecting over-hanging member and on the lower side in an up-turned claw.

35 In testimony whereof, I have signed my name to this specification this 13th day of January, 1928.

JOSEPH A. HOEGGER.
